[57] CLAIM

The ornamental design for data logging device components, as shown.

DESCRIPTION

FIG. 1 is a top, front, and left side perspective view of a data logging unit showing my new design;
FIG. 2 is a bottom, rear, and right side perspective view thereof;

FIG. 3 is a top, left side perspective view thereof, with two parts of the unit separated from one another.

Fig. 1.

Fig. 2.
